CLAIM

We claim the ornamental design for a biopsy device, as shown and described.

DESCRIPTION

FIG. 1 is a perspective view of the front, top and left side front of the biopsy device;

FIG. 2 is a right side view of the biopsy device;

FIG. 3 is a left side view of the biopsy device;

FIG. 4 is a top elevation view of the biopsy device;

FIG. 5 is a bottom elevation view of the biopsy device;

FIG. 6 is a front view of the biopsy device; and,

FIG. 7 is a rear view of the biopsy device.
